UNITED STATES PATENT OFFICE

ABRAHAM POLLAK, OF FAR ROCKAWAY, NEW YORK, ASSIGNOR TO ART METAL WORKS, INC., OF NEWARK, NEW JERSEY, A CORPORATION OF NEW JERSEY

LIGHTER

Application filed January 10, 1929. Serial No. 331,476.

This invention relates to improvements in automatic lighters.

One of the objects of this invention is to produce a lighter operable to light upon the movement of a sliding element in one direction and preferably upon movement of a wind shield mounted on the top of a reservoir.

Another object is to produce a lighter of the type above specified in which movement of the said slide in the reverse direction will extinguish the light, and in which said reverse movement will be accomplished automatically.

Another object of this invention is to produce a lighter operable upon the movement of a sliding element to move a wick cap to uncover the wick and simultaneously to rotate a flint wheel to cause a shower of sparks from a pyrophoric element to light said wick and thereafter by a reverse movement of said slide automatically to reset said sparking apparatus for operation and to extinguish the light.

Still another object of my invention is to provide simple and inexpensive connecting mechanism between an operating sliding element and a rotatable sparking wheel whereby movement of the sliding element in one direction will cause a shower of sparks to be thrown toward a wick in a direction opposite to the movement of said operating slide.

Still another object of the invention is to produce a lighter operable by the movement of a sliding wind-shield mounted on the top of a reservoir from the forward to the rear edge thereof to cause a movement of a hood and sparking element in anti-clockwise direction to throw a shower of sparks forwardly toward a wick arranged between said sparking mechanism and the front edge of the casing.

Still another object of my invention is to combine such simplified spark-wheel operating-mechanism with a wick-extinguishing cap to cause a lifting movement of the cap simultaneously with the operation of the spark wheel and an automatic extinguishing movement thereof by a spring-pressed reverse movement of the slideable wind-shield.

Still another object of my invention is to provide such an operative connection between a slide and a spark-wheel so as to procure the necessary quick-acting spark-throwing movement of the spark-wheel upon a relatively slight manual movement of the slide.

Still another object of my invention is to provide such a simple operative eccentric connection between a slide and spark wheel preferably comprising a disc, having an operative eccentric connection on one side with a slide through a vertical slot in the slide and having at the opposite side an eccentric connection with operating means for the spark-wheel and wick-extinguishing cap.

Still another object of my invention is to provide on the top plate of a reservoir a slide element and preferably a wind-shield movable in guideways rearwardly and forwardly on said top plate, and arranged for manual movement in one direction and spring means for moving the same automatically in the opposite direction, said slide element being operable manually to throw a shower of sparks toward the wick and preferably to simultaneously raise a wick-extinguishing element, and being operable by a reverse automatic movement of the slide to reset the sparking mechanism in position for another operative movement and to simultaneously move the wick cap to extinguishing position.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:

Fig. 1 is a side elevation of a lighter embodying my invention, showing the parts in inoperative position;

Fig. 2 is a view similar to Fig. 1, showing the slide after having been moved rearwardly to raise the cap and ignite the wick;

Fig. 3 is a longitudinal section, showing the parts in normal position;

Fig. 4 is a section similar to Fig. 3, showing the parts in operative position with the cap raised and wick ignited;

Fig. 5 is a fragmentary view similar to Fig. 5 with a part of the shield cut away and the section of the shield being taken on the line 5—5 of Fig. 7;

Fig. 6 is a view similar to Fig. 5, showing the parts in operative position with the wick ignited and the cap raised;

Fig. 7 is a plan view of the device shown in Figs. 1 to 6 with the parts in operative position with the cap raised and wick ignited;

Fig. 8 is a section on the line 8—8 of Fig. 5;

Fig. 9 is a section on the line 9—9 of Fig. 5;

Fig. 10 is a section on the line 10—10 of Fig. 5;

Fig. 11 is a detailed view, in perspective, of my eccentric operating connection between 20 igniting and extinguishing parts of the mechanism;

Fig. 12 is a detailed sectional view, showing pawl and ratchet mechanism for connecting the hood with the spark-wheel, the section being taken on the line 12—12 of Fig. 13; and

Fig. 13 is a bottom view of the cap and hood shown in Fig. 12.

Referring now to these drawings, which illustrate a preferred embodiment of my invention, 1 indicates a fuel reservoir of the conventional type having a top plate 1' and a bottom plate 1^a provided with the usual cap 2 for permitting fuel to be charged into the reservoir. A wick 3 passes at its upper end

35 through a tubular wick holder 3' screwed into the top plate 1' and in the form illustrated, a pyrophoric tube 4 extends vertically through the reservoir and through said top plate 1' and is provided with a pyrophoric element 5 which is normally forced upwardly by a

40 spring 6 into operative engagement with a spark-wheel 7 mounted on a shaft or spindle 8 supported in oppositely-disposed upright brackets 9 which, in the preferred form of my invention shown, are formed in one piece with a track-spacing plate 9' resting upon the top of the reservoir and fastened to the top plate by the wick tube and by the pyrophoric tube.

Also mounted on and fastened to the top plate 50 by the wick holder and pyrophoric tube is a track plate 10. The plate 10 is wider than the plate 9' and forms on opposite sides of the plate 9' and between the top plate 1' and said plate 10 grooves 11, 11' in which grooves is

55 slidably mounted by means of inwardly-directed flanges 12', 12^a an operating element 12 which, in the form shown, comprises a wind-shield and extends around and is normally flush with the perimeter of the top plate 1'

60 and preferably has at its front end a knob 12^b for manual operation. The slideable operating element 12 is normally held in its forward position flush with the perimeter of the top plate 1' by means of a spring 13 surrounding a plunger pin 14 and preferably

partially enclosed within a casing or tube 15 mounted on the track-plate 10.

It is necessary in devices of this type to procure a rapid rotation of the spark-wheel in order to procure a sufficient shower of sparks to ignite the wick and, in the present embodiment of my invention, I have not only provided a quick-acting mechanism but have provided means for operating this mechanism from a slideable element movable in a direction opposite to that in which the igniting sparks are thrown and, furthermore, have provided a simple operative connection as opposed to a compound gearing connection between such a slide and the ignition wheel, the compound gearing connection being too complicated and impractical for devices of this character.

In order to accomplish my purpose, I provide in the slideable element which, as aforesaid, in the form shown comprises a wind-shield, a vertical slot 12^c and make a connection through this vertical slot with an eccentric on a pivoted swinging member operable to produce a rapid rotation of the spark-wheel and to cause a shower of sparks from the pyrophoric element 5 to be thrown in a direction opposite to the movement of the slide. As illustrated, my swinging element preferably comprises a swinging hood 16 having a pivotal movement on the shaft 8 and having a connection disposed eccentric of its pivot with vertical slot 12^c in the slideable wind-shield 12.

In the preferred embodiment of my invention, the eccentric connection between the hood 16 and the slide 12 is formed by mounting axially on the outer end of the shaft 8 between the bearing brackets and the slide 12 discs 17. Said discs are provided on one face with an eccentric projection 17' extending through arcuate guide slots 9' in the bearing brackets 9 to engage opposite sides of the swinging hood eccentrically and said discs have on their other faces eccentric projections 17^a extending into the vertical slots in the slideable wind-shield. Thus a movement of the slide 12 will exert pressure on the eccentric projections 17^a so as to cause them to move upwardly in the slots 12^c and the discs 17 on which the eccentric projections are mounted, to rotate. This rotation of the discs which, as aforesaid, carry on their opposite faces eccentric projections 17', cause the abrupt upward swinging of the hood 16. Said hood has an operative connection with the spark-wheel and the abrupt swinging movement of the hood and the similar abrupt turning of the spark-wheel connected therewith will cause a shower of sparks immediately to be thrown in the direction opposite to the movement of the slideable wind-shield and toward the wick.

As illustrated, I provide a connection between the hood and spark-wheel to cause the

spark-wheel to be driven in one direction only during the movement in opposite directions of the hood, and to this end, the spark-wheel is fixedly mounted on a sleeve 18 5 formed integral with a ratchet wheel 19, said sleeve and ratchet wheel being loosely mounted on the shaft 8, and a pivoted pawl 20, carried by the hood 17 and, as shown, pivoted on a pin 20', is normally pressed into operative 10 engagement with the ratchet wheel 19 by a flat spring 21 also mounted on the hood 16.

As illustrated, the hood 16 also preferably carries a wick-extinguishing cap 22 and in the form illustrated, the cap 22 and spring 21 15 are fastened to the hood 16 by a single screw 23. Obviously upon movement of the hood 16 in the upward direction by the slide 12, the pawl and ratchet wheel 19 will connect the hood to the spark wheel for movement 20 in one direction, the pawl 20 engaging a tooth of the ratchet wheel and that movement in the opposite direction of the hood by the spring 18 will cause the pawl simply to click over the teeth of the ratchet wheel 19.

25 Operation of the device will be apparent from the above description.

Having described my invention, I claim:—

1. A lighter embodying, in combination, a fuel reservoir having a top plate, sparking 30 mechanism mounted upon said top plate including a rotatably-mounted spark-wheel, a wick tube projecting above said top plate, an operating element for said spark-wheel slidably mounted on said reservoir, said 35 spark-wheel having associated therewith an eccentric projection extending laterally and said operating element having a slot connection with said projection.

2. A lighter embodying, in combination, 40 a fuel reservoir having a top plate, sparking mechanism mounted upon said top plate including a rotatably-mounted spark-wheel, a wick tube projecting above said top plate, an operating element for said spark-wheel slidably mounted on said reservoir, said 45 slideable operating element and spark-wheel having an operative connection arranged eccentrically of the spark-wheel and through a vertical slot in said operating element.

50 3. A lighter embodying, in combination, a fuel reservoir having a top plate, sparking mechanism mounted upon said top plate including a rotatably-mounted spark-wheel, a wick tube projecting above said top plate, an 55 operating element for said spark-wheel slidably mounted on said top plate, a pivoted hood mounted over said spark-wheel, said slideable operating element, spark-wheel and hood having an operative connection arranged eccentrically of the spark-wheel and 60 hood and through a slot in said operating element.

4. A lighter embodying, in combination, a fuel reservoir having a top plate, sparking 65 mechanism mounted upon said top plate in-

cluding a rotatably-mounted spark-wheel, a wick tube projecting above said top plate, an operating element for said spark-wheel slidably mounted on said top plate, a pivoted hood mounted over said spark-wheel, said 70 slideable operating element, spark-wheel and hood having an operative connection arranged eccentrically of the spark-wheel and hood and through a slot in said operating element, and a wick-covering and extinguishing cap carried by said hood. 75

5. A lighter embodying, in combination, a fuel reservoir having a top plate, sparking mechanism mounted upon said top plate including a rotatably-mounted spark-wheel, a wick tube projecting above said top plate, an operating element for said spark-wheel slidably mounted on said top plate and adapted to be moved in one direction, a pivoted hood mounted over said spark-wheel, said 80 slideable operating element, spark-wheel and hood having an operative connection arranged eccentrically of the spark-wheel and hood and through a slot in said operating element, a spiral spring and plunger arranged in a casing on the top of said reservoir for moving said operating element in the 85 opposite direction. 90

6. A lighter embodying, in combination, a fuel reservoir having a top plate, sparking mechanism mounted upon said top plate including a rotatably-mounted spark-wheel, a wick tube projecting above said top plate, an operating element for said spark-wheel slidably mounted on said top plate and adapted to be moved in one direction, a pivoted hood mounted over said spark-wheel, said 95 slideable operating element, spark-wheel and hood having an operative connection arranged eccentrically of the spark-wheel and hood and through a slot in said operating element, a spiral spring and plunger arranged in a casing on the top of said reservoir for moving said operating element in the opposite direction, said operating element comprising a wind-shield, and means for limiting the movement of said wind-shield in opposite directions. 100 105 110

7. A lighter embodying, in combination, a fuel reservoir having a top plate, sparking mechanism mounted upon said top plate including a rotatably-mounted spark-wheel, a wick tube projecting above said top plate, an operating element for said spark-wheel slidably mounted on said top plate and adapted to be moved in one direction, a pivoted hood mounted over said spark-wheel, said slideable operating element, spark-wheel and hood having an operative connection arranged eccentrically of the spark-wheel and hood and through a slot in said operating element, and a spiral spring and plunger arranged in a casing on the top of said reservoir for moving said operating element in the opposite direction. 115 120 125 130

8. A lighter embodying, in combination, a fuel reservoir having a top plate, sparking mechanism mounted upon said top plate including a rotatably-mounted spark-wheel, a wick tube projecting above said top plate, an operating element for said spark-wheel slidably mounted on said top plate, a pivoted hood mounted over said spark-wheel, said slideable operating element and hood having an operative connection arranged eccentrically of the hood and through a slot in said operating element, a ratchet wheel and pawl connection between said hood and spark-wheel, and a wick-extinguishing cap carried by said hood.
9. A lighter embodying, in combination, a fuel reservoir having a top plate, a pyrophoric tube extending through said top plate, a spark-wheel rotatably mounted adjacent to said pyrophoric tube, track grooves on said reservoir, a wind-shield slidably mounted in said track grooves, a hood arranged about said sparking mechanism, a ratchet wheel and pawl for connecting said sparking mechanism and hood to rotate in one direction, a wick-extinguishing cap carrier by said hood, and a connecting element comprising a disc disposed between said hood and wind-shield, having an eccentric connection with said hood and having a slot and pin connection with said slideable wind-shield.

In witness whereof, I have signed my name to the foregoing specification.
